DESIGN FOR A JAR OR SIMILAR CONTAINER

Darrell E. Briner, Winchester, Ind., assignor to Leslie A. Lummis, doing business as Lummis Glass Company, New York, N. Y.

Application March 17, 1939, Serial No. 83,642

Term of patent 7 years

To all whom it may concern:

Be it known that I, Darrell E. Briner, a citizen of the United States of America, residing at Winchester, county of Randolph, and State of Indiana,
have invented a new, original, and ornamental Design for a Jar or Similar Container,
of which the following is a specification, reference
being had to the accompanying drawing, forming a part thereof.

tainer showing my new design.

I claim:

The ornamental design for a jar or similar container, as shown.

DARRELL E. BRINER.
